UNITED STATES PATENT OFFICE.

HENRY C. OSBORN, OF CLEVELAND, OHIO, ASSIGNOR TO THE AMERICAN MULTIGRAPH COMPANY, OF CLEVELAND, OHIO, A CORPORATION OF OHIO.

PRINTING MACHINE.

Application filed January 25, 1926. Serial No. 83,451.

This invention relates to office printing machines primarily adapted for printing on envelopes, cards, tags and the like. The primary object of the invention is to provide a simple and efficient means for enabling ready change of the printing characters or a portion thereof as desired. More particularly it is an object to provide a segmental type holder carrying arcuate lines made up of individual type, means which will not complicate the segmental holder being provided to retain the lines in place and allow their removal for the purpose of quick change of the form set up; and generally it is an object to render the construction simple and economical in manufacture and efficient and durable in service.

My printing machine is well adapted for cancelling stamps, as it is adapted to operate equally well on articles of various thicknesses arranged indiscriminately. The machine however may with advantage be put to other uses.

A convenient embodiment of my invention is illustrated in the drawings hereof, and is hereinafter more fully described and the essential characteristics are summarized in the claims.

Fig. 1 is a front elevation of my printing machine; Fig. 2 is a vertical cross section, as indicated by the line 2—2 on Fig. 1; Fig. 3 is a vertical longitudinal section, as indicated by the line 3—3 on Fig. 2; Fig. 4 is a detail of the inking roller and its support, being a vertical section on the line 4—4 on Fig. 2; Fig. 5 is a detail illustrating the support of the paper detecting lever, being a vertical section on the line 4—4 on Fig. 2; Fig. 6 is an elevation illustrating the detector control of the eccentrically mounted platen, being a vertical section on the line 6—6 on Fig. 1 looking toward the right; Fig. 7 is an enlarged vertical cross-section of the rotary printing member, as indicated by the line 7—7 on Fig. 1; and Fig. 8 is a detail illustrating a system of latches for retaining the removable printing lines, being a section substantially on the line 8—8 on Fig. 7 but partly broken away.

The frame of my machine is shown as consisting of a pair of upright end plates 10 and 11, a connecting front cross plate 12

and certain cross rods. Journalled in the end plates is the main shaft 20 on which is mounted the printing segment 30, adapted to be revolved thereby, and carrying the printing form, and below this main shaft is a shaft 50 on which is mounted the roller platen 52 adapted to coact with the printing segment. A suitable inking roller 120 co-acts with the segment when rotated. Accordingly as the shafts 20 and 50 are revolved, paper fed between the segment and platen may be suitably impressed by a type form on the segment.

The type segment is yieldingly carried so that it may give back from the platen according to different thicknesses of material fed between them. The drawing shows an efficient means for accomplishing this, which however is not claimed in this application, but in my preceding application No. 30,658 filed May 16, 1925. As shown, I mount a double arm 24 and 25 having a hub 22 to the other end of which is secured a disk 23, as by screws. The segment 30 near one end has an inward ear 31 which lies between the disk 23 and the arm 25, and a pin 32 occupying these parts pivots the segment to the rotatable member.

To a block 33, rigidly bolted to the inner face of the segment near its other end is pivoted a rod 34 which extends loosely through a head 35 carried by the rigid arm 24. Nuts 36 on this rod limit the outward movement of the segment while a compression spring 37 surrounding the rod between a head 38 thereon and the head 35 yieldingly holds the segment in printing position but allows it to give back according to the thickness of the material fed between the segment and platen.

The segment is provided with overhanging parallel rails 40, providing undercut channels adapted to retain grooved type T. To allow the type to be readily slid into place between the rails and locked therein, I provide the mechanism shown in Figs. 7 and 8, comprising a system of latches for the respective channels between the rails. As there shown, I mount a series of blocks 42 in the space 43 between the segment proper and a radial portion of the block 33 to which the rod 34 is pivoted. Each of these blocks

42 is substantially L-shaped and carries a pin 44 slideable through the block 33. A compression spring 45 surrounds the pin and normally holds the block in the outermost 5 position, as shown in Fig. 7.

When it is desired to mount type in the channel or remove it therefrom, the corresponding block 42 is pressed inwardly as may be readily done by the operator's finger 10 or with the transfer tool which delivers the type or receives it from the segment. When a block 42 is pressed inward (as shown in the case of one block in Fig. 8) the corresponding channel is free and the type row, or a 15 portion of it, may be installed or removed, after which the block returns to lock it to position. At the other end of the channels I prefer to mount a stop 48 shown as an L-shaped bar of metal held by a screw 49. The 20 construction described enables the type to be very readily changed.

The platen 52 with which the segment contacts is shown as a long roller mounted on the shaft 5 which is connected by gears 60 and 25 61 with the segment shaft 20. I have shown a hand crank 65 mounted on a stud at one end of the machine and carrying a gear 66 meshing with a gear 67 on the segment shaft, and this is a convenient way of driving the 30 machine by hand power.

I have shown mechanism preventing the operation of the machine when paper is omitted.

As shown in Fig. 3, the platen shaft 50 is mounted at one end adjacent the segment eccentrically in a bushing 70 which is rotatably mounted in the frame member 10. On this bushing is an arm 71 (Fig. 6) pivoted to a flat bar 73 slotted about the segment 40 shaft 20. This bar carries a roller 74 co-acting with a cam 75 secured to the segment disk 23. Accordingly, each rotation of the segment shaft turns the eccentric to raise that end of the platen into position to be 45 active, this being the position shown in Fig. 6. As there shown, the platen is raised, while the printing segment 30 is out of registration with the platen. Now, unless the paper detector acts by reason of the presence 50 of paper, the cam will pass beyond the roller and the slide will be freed and the spring 76 thereon will restore the platen to idle position.

The paper detector mechanism comprises 55 a lever or finger 80 pivotally mounted on a longitudinal rod 81 and connected with a rock arm 82 which is adapted to bear against a dog 84 pivoted at 85 to the frame of the machine. The upper end of this dog stands 60 normally opposite, but free from, a notch 78 in the slide 70, being retained in this position by a spring 86. When no paper is present, the detector mechanism described is idle.

65 The finger 80 it will be noticed, extends

into a peripheral groove 54 in the platen, so that it is impossible for paper to be fed to be gripped above the platen without raising the lever. When the finger is so raised it rocks upwardly on the arm 82 which 70 thus rocks the dog into the notch 78; thereafter when the cam 75 clears the roller 74, the slide cannot return to its normal down position but is held by the dog, and thus the platen is maintained in its active position 75 throughout the time the segment is moving past the platen whereby printing is effected.

To prevent jamming of the parts and allow the finger 80 to be raised at any time irrespective of the position of the notch 78 with reference to the dog 84, I connect the dog tripping arm 82 yieldingly with the detector finger 80. As shown in Fig. 5, the detector arm is pinned to a hub 87 on the shaft 81. Pinned to the other end of this hub is a short rock arm 88 which is connected by a spring 89 with the dog-operating arm 82. This spring 89 is stronger than the spring 86 acting on the dog.

It will be seen that if the detector arm 80 is raised at a time when the notch 78 is opposite the dog 84, the two arms 88 and 82 act as a unit, swinging the dog into the notch. If however, the detector arm is raised at any other time the spring 89 is constrained, forcing the dog against the edge of the slide 70 so that it will pass into the notch as soon as the notch comes opposite the nose of the dog.

In the interest of simplicity, I prefer to provide the eccentric bearing described for only one end of the platen. I find I can effect this by allowing a slight looseness of fit of the platen shaft with its bearing in the standard 11. The platen shaft is parallel with the segment shaft when the platen is raised into active position, and the slight divergence from parallelism when the platen is inactive is immaterial.

Fig. 2 illustrates a simple elastic stop limiting the hand-fed sheet until it is gripped by the segment and platen. This elastic stop comprises a spring finger 100 mounted on a frame rod 101 and a cooperating spring pressed finger 102 mounted on a frame rod 103. This latter finger is preferably pivotally mounted on a block 104 which is adjustably clamped to the rod by a screw 105. A spring 106 mounted in a recess in the block forces this finger against the finger 100. A suitable recess 56 in the platen accommodates the engaging ends of these fingers.

The paper is normally fed by hand along the paper table 108 until stopped by the engaging ends of the fingers 100 and 102. In this same movement, the forward edge of the paper raises the detector arm 80 which thus, by the mechanism already described, operates to hold the platen in its raised po- 125 130

sition, after it has been raised by the cam mechanism. Thus the paper may be advanced by hand at any time, and, at the proper time, it is picked up by the machine, 5 fed through it and printed; while if, for any reason paper is absent, the printing member and platen remain out of contact.

Figs. 1, 2 and 5 illustrate a convenient paper ejector. This comprises a roll 110 on 10 a frame rod 111 and a surmounting roll 112 carried in the sheet metal cage 115, pivoted on the rod 81. This cage is pressed downwardly by a spring 118 which is mounted within the cage has one end anchored to 15 the rod and the other to the cage.

To ink the segment I have illustrated the felt roller 120. This is shown as comprising felt disks mounted on a hub 121 which has a hollow bearing sleeve 112 mounted on 20 a stud 123. This stud is carried by a block 124 mounted in a recess 15 in the inner face of the frame member 10. The block is slotted and a pin 125 passes through the slot and through the frame member and has on 25 its end a wing nut 127 to lock the parts together. Thus the block may be adjusted toward or from the printing member, bringing the inking roller into proper position with reference to the segment, and the wing 30 nut then locks the parts in this adjusted position. I may replace the inking roller without changing its mounting, by simply removing a pin 128 from the stud 123 and sliding off the complete inking roller.

Having thus described my invention, I claim:—

1. A printing member having adjacent overhanging parallel rails providing an undercut channel between them, a slidable block, and a spring normally maintaining it opposite the end of the channel, said block being movable to allow access to the channel.

2. In a printing machine, the combination 45 of a printing member parallel undercut type channels on the face of the member located close to each other so that all may hold a unitary form, and a series of adjacent, individually movable locking blocks one for each channel.

3. In a printing machine, the combination 55 of a printing member, parallel undercut type channels on the face of the member, a series of locking blocks one for each channel, and a series of springs for maintaining said blocks normally across the ends of the respective channels.

4. In a printing machine, the combination 60 of a rotary carrier, a segment adjacent its swinging end thereon pivotally mounted at one end and having on its convex face a series of arcuate parallel undercut type channels,

and a series of locking blocks one for each channel movably mounted on the segment.

5. In a printing machine, the combination 65 of a revolving segment, parallel arcuate rails mounted on the face thereof and having overhanging edges, a stationary abutment at one end of the channels as provided, a series of individual abutments at the other end comprising slidably guided blocks having pins connected therewith, and slidable in the openings in the carrier, and spring surrounding said pins and pressing the blocks toward the ends of the channels.

6. In a printing machine, the combination 70 of a rotary carrier, a segment pivoted therein, a spring for pressing the segment outwardly, parallel arcuate rails mounted on the face of the segment, a series of individual blocks slidably guided substantially radially on the segment adjacent the ends of the channels, springs pressing said blocks normally into position to overhang the channels, there being clearance enabling the 75 blocks to be pressed inwardly against the action of the springs to free the channels.

7. In a printing machine, the combination 80 of a carrier having an undercut channel in which a row of grooved type may be mounted, a movable end gate for the channel, a spring pressing said end gate in a direction toward the plane of the face of the type, and a stop to limit such movement of the gate, the gate being movable against the action of 85 the spring to free the type.

8. In a printing machine, the combination 90 of a carrier having parallel rails providing adjacent undercut type channels adapted to hold rows of individual type to make up a form, and individual means for locking each row independently on the carrier, said means being movable to free such row.

9. In a printing machine, the combination 95 of a printing member having parallel rails with overhanging edges adapted to hold between them rows of grooved type, individual gates at the end of the respective rows, each gate comprising a slidable block carrying a guiding pin, springs surrounding the respective pins for forcing the blocks outwardly and lips on the blocks limiting the outward movement.

10. In a printing machine, the combination 115 of a segmental type carrier having on its convex face a series of parallel channels, and individual end gates for the respective channels, means for holding them across the ends of the channels and means enabling them to be moved inwardly, substantially radially, to release the channels.

In testimony whereof, I hereunto affix my signature.

HENRY C. OSBORN.
